UNITED STATES PATENT OFFICE

166,503

CASING FOR AN AMUSEMENT GAME

Harry L. Skelly and Edith Freedman, Reno, Nev.

Application November 5, 1951, Serial No. 17,279

Term of patent 14 years

(Cl. D52—3)

To all whom it may concern:

Be it known that we, Harry L. Skelly and Edith Freedman, citizens of the United States, both residing at Reno, State of Nevada, have invented a new, original, and ornamental Design for a Casing for an Amusement Game, of which the following is a specification, reference being had to the accompanying drawing, forming a part hereof.

Fig. 1 is a front perspective view of a casing for an amusement game, showing our new design;

Fig. 2 is a side perspective view of the casing for an amusement game;

Fig. 3 is a back perspective view thereof.

We claim:

The ornamental design for a casing for an amusement game, substantially as shown.

HARRY L. SKELLY.
EDITH FREEDMAN.
